ADJUSTABLE SUPPORT

Filed Dec. 30, 1944

2 Sheets-Sheet 1

Fig. 1.

A technical line drawing of a mechanical assembly, labeled 'Fig. 2.' in the upper left corner. The drawing shows a cross-section of a cylindrical component with various internal and external features. Key parts are labeled with numbers: 20, 21, 22, 23, 24, 25, 26, 27, 28, 29, 30, 33, 34, 38, and 39. The drawing illustrates a complex assembly with a central shaft, a housing, and various bearings and seals.

ADJUSTABLE SUPPORT

Elmer G. Gartin, Claremont, N. H., assignor to
Joy Manufacturing Company, a corporation of
Pennsylvania

Application December 30, 1944, Serial No. 570,626

4 Claims. (Cl. 255—51)

1

This invention relates to adjustable supports and more particularly to an improved adjustable support for a drifter type rock drill.

In drilling rock, as in tunnel work, rock drills are oftentimes mounted on a portable carriage commonly known as a rock drill "jumbo" embodying a swingable boom pivoted on a portable base and carrying the rock drill at its outer extremity. In such drill supports it is desirable to maintain the drill supporting boom steady during the drilling operation, and a vertical jack or column is sometimes provided to secure the boom firmly between the tunnel roof and floor. The swingable boom should be firmly clamped to the column, and it is desirable to provide a clamping device which may be readily and quickly adjusted.

An object of the present invention is to provide an improved adjustable support. Another object is to provide an improved adjustable support embodying a swingable drill supporting boom, an upright column or jack and means for firmly securing the boom to the column to maintain the boom steady during the drilling operation. A further object is to provide an improved clamping device comprising clamps engageable with a boom and with a column respectively and having a swivel between the two clamps, together with common operating means for firmly locking the clamps and swivel in adjusted position. A still further object is to provide an improved triple clamp having a common operating bolt for tightening or loosening the three clamps concurrently. These and other objects and advantages of the invention will, however, hereinafter more fully appear.

In the accompanying drawings there is shown for purposes of illustration one form which the invention may assume in practice.

In these drawings:

Fig. 1 is a side elevational view of the forward portion of a rock drill carriage or "jumbo" with which an illustrative form of the invention is associated.

Fig. 2 is an enlarged horizontal sectional view taken substantially on line 2—2 of Fig. 1.

Fig. 3 is a plan view of the drill carriage shown in Fig. 1.

Fig. 4 is a vertical sectional view taken on line 4—4 of Fig. 2.

In this illustrative embodiment of the invention, the improved adjustable support or clamping device 1 is shown associated with a portable drill carriage or "jumbo" generally designated 2. Evidently, the invention may be embodied in other types of apparatus.

2

The portable drill carriage or "jumbo" 2 includes a truck frame 3 adapted to travel along a trackway 4 laid on the tunnel floor. Swiveled on the forward portion of the truck frame to turn about a vertical axis is a support 5 on which a boom 6 is pivotally mounted at 7 for swinging movement in a vertical direction. A power jack device 8 is preferably employed to effect vertical swinging movement of the boom, and the latter carries at its outer end a yoke-shaped frame 9 supporting a crossbar 10. A drifter type hammer rock drill 11 is secured to the crossbar 10 and has a hammer motor 12 for percussively actuating a drill steel 13. A feeding means embodying a feeding motor 14 is provided for feeding the rock drill back and forth along a guide frame 15 on which the drill is slidably guided. A clamping device 16 is provided for firmly clamping the guide frame 15 to the crossbar 10.

10 A vertical jack or column 17 may be secured between the tunnel roof and floor in the manner shown most clearly in Fig. 1, for holding the drill supporting boom 6 steady during the drilling operation, and the improved clamping device 1 is

25 provided for firmly securing the boom and column together.

The improved adjustable support or clamping device 1 comprises a pivoted clamp 20 (Fig. 2) having jaws 21 and 22 pivoted together at 23, 30 and these jaws are engageable with the body of the vertical jack or column 17. Cooperating, relatively rectilinearly movable parts 24 and 25 of a clamp 26 (Fig. 4) are engageable with the drill supporting boom 6. The clamp part 25 has 35 a conical or tapered portion 27 received in a conical socket 28 on the clamp jaw 22. A U-clamp 29 engages the outer clamp part 24 and a cross-bolt 30 passes through an elongated slot 31 in the clamp part 25 and through openings 32 40 in the arms of the U-clamp 29, as shown in Fig. 4. An eyebolt 33 projects within a recess 34 in the clamp part 25 and engages the crossbolt 30 midway between its ends. The eyebolt 33 extends through aligned openings 35 and 36 in the clamp 45 parts 22 and 25 respectively, and also through the notch 37 in the clamp jaw 21; and an adjusting nut 38 engages the outer threaded portion 39 of the eyebolt. When the adjusting nut 38 is tightened, the three clamps are concurrently 50 moved into clamping position. When the eyebolt is tightened, the clamping jaws 21 and 22 are drawn toward one another to grip firmly the column 17, and the tapered portion 27 is drawn within the socket 28 firmly to lock the swivel. 55 At the same time the clamp parts 24 and 25 are

drawn toward one another by the U-clamp 29 so long as the cross-bolt 30 has sufficient play in the slot 31 firmly to grip the drill supporting boom 6. Thus, by tightening a single nut on the eyebolt, the three clamps are adjusted concurrently into clamping position. Conversely, when the nut 38 is loosened, the three clamps are concurrently released. Accordingly, when it is desired to swing the drill supporting boom, the clamping device may be quickly released, and when the boom is in the desired position, the clamping device may be quickly adjusted into clamping position.

As a result of this invention, an improved adjustable support or clamp is provided which may be readily and quickly moved into and out of adjusted position. It will further be apparent that, by the provision of the improved clamping device, the drill supporting boom of the drill carriage may be firmly held in drill supporting position. By the provision of the single adjusting element for a triple clamp, the three clamps may be concurrently tightened or loosened as desired, and since but a single element needs adjustment to effect clamping, clamping may be expeditiously effected. Other uses and advantages of the invention may be clearly apparent to those skilled in the art.

While there is in this application specifically described one form which the invention may assume in practice, it will be understood that this form of the same is shown for purposes of illustration and that the invention may be modified and embodied in various other forms without departing from its spirit or the scope of the appended claims.

What I claim as new and desire to secure by Letters Patent is:

1. A triple clamping device comprising a pair of clamps having a swivel therebetween, and adjustable means including a single adjusting element common to the adjustment of said clamps and swivel for concurrently tightening said clamps and for locking said swivel.

2. A triple clamping device comprising a clamp having a pair of cooperating clamp elements, a second clamp having a pair of cooperating clamp

elements, one of said first clamp elements having a socket for receiving a swivel portion and one of said clamp elements of said second pair having a swivel portion received in said socket, and adjusting bolt means common to the adjustment of said clamps and swivel and having portions cooperating with elements of both clamps for concurrently tightening said clamps and for locking said swivel.

3. A clamping device comprising a clamp having a U-clamp portion and a cooperating cross-bolt for adjusting the same, a second clamp having an eyebolt engaging said crossbolt, and a nut threaded on said eyebolt and common to the adjustment of said clamps for concurrently adjusting said eyebolt and said U-clamp portion tightly to hold said clamps in gripping position.

4. In combination, a column, a boom pivotally mounted for vertical swinging movement alongside said column, and means for rigidly fixing said boom to said column in different relative positions including clamp devices between which and said boom and column relative sliding movement is possible upon release of said clamp devices, a pivotal connection between said clamp devices permitting angular adjustment between the same as the boom is raised and lowered and the relative positions between said devices and said boom and column are changed, and adjustable means including a single adjusting element common to said clamp devices and said pivotal connection for concurrently tightening said clamp devices and said pivotal connection.
